(57) **CLAIM**

The ornamental design of an in-sink dishwasher with single bowl, as shown and described.

DESCRIPTION

FIG. 1 is a front perspective view of the in-sink dishwasher with single bowl showing the new design;

FIG. 2 is a top perspective view with lid open thereof;

FIG. 3 is a top plan view thereof;

FIG. 4 is a front elevational view with lid open thereof;

FIG. 5 is a rear elevational view with lid open thereof;

FIG. 6 is a left elevational view with lid open thereof; and,

FIG. 7 is a top plan view with lid open thereof.

The broken lines shown are for illustrative purposes only and form no part of the claimed design.
